CLAIM

The ornamental design for a Christmas tree waterfall light, as shown and described.

DESCRIPTION

FIG. 1 is a perspective view of a Christmas tree waterfall light design showing our new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading and cross-hatching are not features of the design but are utilized to illustrate the surface contours of the Christmas tree waterfall light design in the drawings. The Christmas tree waterfall light is shown with a symbolic break in its length, represented by wavy lines. The appearance of any portion of the article between the wavy lines forms no part of the claimed design.
